CLAIM

(21) **Appl. No.:** **29/747,146**

The ornamental design for a vehicle display screen or portion thereof with graphical user interface, as shown and described.

(22) **Filed:** **Aug. 20, 2020**

DESCRIPTION

(30) **Foreign Application Priority Data**

Feb. 27, 2020 (DE) 402020100201.1

This application contains subject matter related to the following co-pending U.S. design patent applications:

(51) **LOC (13) Cl.** **14-04**

Application Ser. No. 29/747,142, filed herewith and entitled “Vehicle Display Screen or Portion Thereof with Graphical User Interface”;

(52) **U.S. Cl.**

Application Ser. No. 29/747,143, filed herewith and entitled “Vehicle Display Screen or Portion Thereof with Graphical User Interface”; and

(58) **Field of Classification Search**

Application Ser. No. 29/747,144, filed herewith and entitled “Vehicle Display Screen or Portion Thereof with Graphical User Interface”.

USPC D14/485-495

The file of this patent contains at least one drawing/photograph executed in color. Copies of this patent with color drawing(s)/photograph(s) will be provided by the Office upon request and payment of the necessary fee.

CPC G06F 3/04847; G06F 3/0485; G06F 3/048;

The sole FIGURE is a front view of a vehicle display screen or portion thereof with graphical user interface according to the design.

G06F 3/0488; G06F 3/0482; G06F 3/167;

The broken line showing of the vehicle display screen is provided for the purpose of illustrating environmental structure and forms no part of the claimed design.
